UNITED STATES PATENT OFFICE

96,955

DESIGN FOR LACE

Leon Birnbaum, New York, N. Y.

Application August 27, 1935, Serial No. 58,315

Term of patent 3½ years

To all whom it may concern:

Be it known that I, Leon Birnbaum, a citizen of the United States of America, residing in Manhattan, county of New York, and State of New York, have invented a new, original, and ornamental Design for Lace, of which the following is a specification, reference being had to the accompanying drawing, forming part thereof, wherein, the figure is a plan view of a piece of lace showing my new design.

I claim:

The ornamental design for lace, substantially as shown.

LEON BIRNBAUM.
